UNITED STATES PATENT OFFICE.

HENRY E. WAITE, OF BRIDGEPORT, CONNECTICUT, ASSIGNOR TO CHARLES F. LIVERMORE, OF SAME PLACE.

TELEPHONE-TRANSMITTER.

SPECIFICATION forming part of Letters Patent No. 250,308, dated November 29, 1881.

Application filed June 8, 1881. (No model.)

To all whom it may concern:

Be it known that I, HENRY E. WAITE, of Bridgeport, county of Fairfield, State of Connecticut, have invented certain new and useful Improvements in Telephone-Transmitters, of which the following is a full and exact description, reference being had to the accompanying drawings, making part of this specification, in which—

10 Figure 1 is a plan or top view of my improved transmitter with the cap-plate or cover removed, and Fig. 2 is a vertical section through the same.

My invention relates to a novel arrangement 15 of the carbon or conductor plates of the transmitter; and it consists in the combination, with a grooved or flanged base-plate of carbon or equivalent material, of inclined plates of similar material resting upon said base-plate 20 and forming a series of two or more light contacts, as hereinafter explained.

In the accompanying drawings, A represents a box or case, made, by preference, of cork; but it may be made of any non-resonant 25 material, within which is placed a block or base-plate, B, of carbon or other suitable conducting material, made, by preference, with vertical flanges b b' at the sides, as shown, and above these are suspended plates C C', either or both, 30 of carbon or its equivalent, said plates being pivoted at d by hooks or eyes, hinging their upper edges to the side walls in such manner as to hold the plates pendent, with their lower edges resting against the inner faces of the 35 flanges b b' or the base-plate B, in such manner as to give them the inclined position shown, in which the tendency of the weight of said plates to swing into a vertical position keeps them in contact with the base-plate B at their 40 lower edges, as shown. Where but a single hinged plate is used the wires will be connected, one with said plate and the other with the base-plate; but where two are used the wires will be connected, one with one of said hinged 45 plates and the other with the other, as shown, the base-plate serving to connect them. These plates, instead of being made in one piece, may be composed of several pieces or sheets resting one upon another, as shown at C', thus 50 producing the multiple contact or number of contacts described in another application, filed

May 23, 1881, and the base-plate B may, if desired, be formed in a similar manner.

The form of the carbon pieces may be varied, of course, so long as the hinged and inclined relation of one part to the other is maintained, adapting it to rest in vibratory contact therewith, and the form of the box, case, or support A also may be changed, its essential feature of construction being that it shall be 55 adapted to support the carbon plates or conductors, one in a suspended and inclined relation to the other, as described, though the enclosing-case of cork or equivalent non-resonant material described is preferred, as in the latter 60 construction the case serves, through molecular disturbance due to the action of the atmospheric sound-waves impinging upon its surface, to convey such disturbance to the microphone. Where other material is used for the 65 case the cover should be raised or left off, so as to expose the microphone to the direct action of the sound-waves.

In the microphone described it will be readily understood that while the parts thereof rest 70 always in contact, such contact is more readily disturbed by the sound-waves or molecular disturbance referred to than where the parts are so arranged that one has to support the 75 entire weight of the others, and the sensitivity of the microphone to the action of the sound-waves or under molecular disturbance is correspondingly increased.

Having now described my invention, I claim—

1. In a telephone-transmitter, the grooved or flanged block, of carbon or equivalent conducting material, in combination with the inclined plates, of similar material, resting in contact with said block on opposite sides thereof, 80 substantially as described.

2. The combination, in a telephone-transmitter, of the flanged block or base-plate, of carbon or equivalent conducting material, and the laminated plates or leaves, of similar material, 85 suspended in an inclined position and resting thereon, for giving a light multiple contact, substantially as described.

HENRY E. WAITE.
